UNITED STATES PATENT OFFICE.

OSCAR C. WIESNER, OF KANSAS CITY, MISSOURI.

VENDING MACHINE.

1,134,305.

Specification of Letters Patent. Patented Apr. 6, 1915.

Application filed January 29, 1914. Serial No. 315,178.

To all whom it may concern:

Be it known that I, OSCAR C. WIESNER, a citizen of the United States, residing at Kansas City, in the county of Jackson and State of Missouri, have invented a certain new and useful Improvement in Vending Machines, of which the following is a specification.

My invention relates to improvements in vending machines.

One of the objects of my invention is to provide a vending machine which is simple in construction, is attractive in appearance, is efficient in operation, which may be readily operated by an inexperienced person and which is not liable to get out of order.

Another object of my invention is to provide a vending machine which may be readily opened by an authorized person for the purpose of supplying thereto the articles to be vended and for removing therefrom the coins which have been deposited therein, but which is protected from being opened by an unauthorized person not provided with a key adapted for use in connection therewith.

Still another object of my invention is to provide a construction of novel design which renders it difficult for any of the articles held therein for vending being extracted therefrom without the deposition therein of the proper coins.

Other novel features of my invention are hereinafter fully described and claimed.

In the accompanying drawings, which illustrate the preferred embodiment of my invention, Figure 1 is a central vertical sectional view of my improved vending machine. Fig. 2 is a plan view of the same with the globe and cover removed. Fig. 3 is a fragmental vertical sectional view on the line 3-3 of Fig. 2. Fig. 4 is a fragmental vertical sectional view on the line 4-4 of Fig. 7. Fig. 5 is a plan view of the machine, partly broken away, and with the bowl, hopper, globe and cover removed. Fig. 6 is a bottom view of the machine, the bottom cover being partly broken away. Fig. 7 is a horizontal section on the line 7-7 of Fig. 1. Fig. 8 is a bottom view of the rotary delivery member. Fig. 9 is a top view of the valve. Fig. 10 is an enlarged view showing partly in elevation and partly in vertical section the key, one of the reversely threaded nuts, and portions of the cap and securing rod.

Similar reference characters designate similar parts in the different views.

The machine is provided with a receptacle adapted to contain the articles to be vended and comprising a globe 1, preferably of glass, and having fitted on its top a removable cover 2 adapted to close the open upper end of the globe, the lower open end of which is supported on a hopper 3 which is mounted in and supported by a bowl 4, which is mounted in a hollow base 5.

A vertical securing rod 6 has its screw-threaded lower end extending through a central vertical hole which is provided in the closed upper end of the base 5.

A nut 7 fitted on the threaded lower portion of the rod 6 bears against the upper side of a washer 8, which in turn rests against the upper end of a sleeve 9 which encircles the rod 6 and has its lower end supported by the upper side of the top of the base 5, as is shown in Fig. 1.

For releasably securing the cover 2 in a closed position on the bowl 1, said cover is provided therethrough with a central hole 10 through which extends to a more or less extent the upper end of the rod 6. The hole 10 is larger in diameter in its upper portion than in its lower portion, and in its enlarged upper portion is adapted to be mounted and wholly contained a nut 11, the opposite ends of which are provided with oppositely or reversely threaded portions 12 and 13. The lower end of the nut 11 is adapted to fit the threaded upper end of the rod 6, for the purpose of retaining the cover 2 tightly against the globe 1.

The rod 6 has extending through it adjacent to its upper end a transverse pin 14, which is adapted to enter two transverse slots 15 which communicate with the hole 10 at the under side of the cover 2. This construction prevents the cap 2 from turning relative to the globe 1 and rod 6.

Preferably the nut 11 is located wholly within the hole 10 to prevent its being gripped and turned without the use of the key 16, Fig. 10, the lower end of which is externally screw-threaded and fitted to the threaded upper portion 13 of the nut 11.

In order to prevent an ordinary screw being used to turn the nut 11 so as to release the cover, the upper end of the rod 6 is provided with an upwardly extending extension 17, which is of less diameter than the threaded upper end of the rod 6 and is adapted to

enter a vertical hole 18 which is provided in the threaded end of the key 16.

When it is desired to remove the cover 2, the threaded end of the key 16 is screwed into the upper end of the nut 11, and when it has reached the limit of its inward movement, it stops turning in the nut 11. Continued pressure applied to the key in a direction tending to screw it into the nut will, 10 by reason of the ends of the nut being reversely threaded, cause the nut to unscrew from the rod 6, after which the nut may be removed with the key, upon which the cover 2 may be removed from the globe 1. By reversing this operation, the cover may be again secured to the globe and the key removed from the nut 11.

The open lower end of the base 5 is normally closed by a removable bottom plate 20 or cover 19, having a central upwardly extending boss 20 through which extends a vertical hole 21. In said hole is located a clamping nut 11' having reversely threaded ends, similar to the nut 11, the upper end of 25 the nut being fitted to the screw-threaded lower end of the rod 6, which extends into the hole 21, and is provided at its lower end with a downwardly extending extension 17', which is adapted to enter the hole 18 of the 30 key 16, the key having its threaded shank fitted to the lower threaded end of the nut 11'. The nut 11' is clamped in position and removed by the key 16 in the manner described with reference to the nut 11.

35 To prevent the plate 19 being turned in the base so as to release the nut 11', said plate is provided with a peripheral notch 22, Fig. 6, adapted to receive an inwardly extending projection 23 on the base 5.

40 A transverse pin 24 in the rod 6 bears against the under side of the top of the base 5, and with the nut 7, washer 8 and sleeve 9, serves to hold the rod 6 tightly clamped to the base 5.

45 The upper side of the base 5 is provided with a central circular boss 25 which supports a rotary article delivery member 26 located in the article receptacle and provided with a plurality of vertical holes 27 therethrough adapted, when the member 26 is rotated step by step, to register with an exit opening 28 through which the articles to be vended are discharged down a chute 29 into a pan 30.

55 A guard 31 having in its upper end a coin chute 32 is secured to the exterior of the base 5, and covers the chute 29 to prevent tampering with the delivery member 26.

To releasably hold the delivery member 60 26 with any one of its holes 27 registering with the exit opening 28, the underside of the delivery member is provided with recesses 33 arranged in a circle concentric with the axis of said delivery member at 65 equal distances apart, and corresponding in

number with the holes 27. The top of the base 5 is provided with a vertical recess 34 in which is mounted a coil spring 35, which normally forces a ball 36 upwardly to a position in which it will enter the recesses 33 consecutively when the delivery member 26 is rotated step by step, Fig. 4.

Pivoted on the boss 25 below the delivery member 26 is an oscillatory valve comprising an arcuate plate 37, Fig. 9, which has a handle 38 extending through a slot 39, which is provided in the base 5. In the valve 37 is provided a radial slot 40, which is adapted to receive a coin 41, shown in dotted lines in Fig. 1, which has been inserted in the chute 32.

In the initial position of the valve 37, the slot 40 is in register with one of the recesses or slots 42 provided in the under side and outer portion of the delivery member 26. At each side of each slot or recess 42 is a projection 43 adapted to be engaged by the coin 41 and to be turned with the member 26 when the valve 37 is turned from the initial position, shown in Fig. 5, to a position in which the slot 40 is in register with a coin discharge slot 44 with which the upper side of the base 5 is provided.

To support the coin 41 in the slot 40, the valve 37 has a bridge portion 45, Fig. 1 and Fig. 5, which cooperates with an arcuate shoulder 46 with which the base 5 is provided. This shoulder 46 forms a coin support, and near its delivery or discharge end is provided with a lock notch 47 into which the coin 41 enters, to prevent the retraction of the valve 37 until after the coin has been discharged into the slot 44.

A helical rod 48 attached to the delivery member 26 serves as an agitator to keep the articles from packing in the article receptacle.

The valve 37 is retracted to its initial position after the coin 41 has been discharged into the slot 44 by a spring 49, which encircles the rod 6, and has one end bearing against a screw 50 in the underside of the valve, the other end of the spring bearing against a projection 51 provided on the underside of the top of the base 5.

In operating my invention, the coin, designated by 41, is inserted in the coin chute 32 and falls into the slot 40 of the valve 37, in which slot the coin is supported by the bridge 45 and the shoulder or coin support 46. If now the valve 37 be turned to the right, as viewed from the front of the machine, the coin 41 will be carried along, and by its engagement with the adjacent projection 43 will turn the delivery member 26 so that a filled hole 27, therein will pass into register with the exit opening 28, the article contained in said hole, however, being still supported by the valve 37, which moves so as to cover said exit opening. After the 130

coin 41 has been discharged into the slot 44, and passes into the hollow base 5, the handle 38 of the valve 37 is released, upon which the spring 49 will retract the valve 37 to its initial position, whereby the exit opening 28 will be uncovered and the article vended will pass down the chute 29 into the pan 30 from which it will be removed by the purchaser. The spring actuated ball 36 will readily lock the delivery member from turning in either direction until another coin has been inserted, and the valve 37 again turned from its initial position to its delivery position.

To prevent articles to be vended passing into the hole 27 which is in register with the exit opening 28, a guard comprising an inwardly extending projection 52 on the hopper 3, is arranged to extend over the exit opening 28 and the hole 27 which is in register therewith.

It is obvious that my improved machine may be employed to vend various kinds of articles, such as balls of chewing gum, candy or other commodities, preferably put up in ball form, so as to be readily fed into the holes 27 of the delivery member.

I do not limit my invention to the structure shown and described as modifications, within the scope of the appended claims, may be made without departing from the spirit of my invention.

Having thus described my invention, what I claim and desire to secure by Letters Patent, is:—

1. In a vending machine, a receptacle for the articles to be vended provided with an exit opening, a rotary delivery member having holes therethrough arranged to consecutively register with said exit opening, a guard covering the hole which is in register with said exit opening, and an oscillatory valve having means for supporting, in connection with said receptacle, a coin in position for engaging and turning said rotary member, when the oscillatory valve is turned from an initial to a predetermined position, said valve being arranged to close said exit opening when moved to said pre-determined position, and to uncover said exit opening when retracted to the initial position.

2. In a vending machine, a receptacle for the articles to be vended provided with an exit opening and having a coin support, a rotary delivery member having holes therethrough arranged to consecutively register with said exit opening, a guard covering the hole which is in register with said exit opening, and an oscillatory valve having means for supporting a coin, in connection with said coin support, in position for engaging and turning said rotary member, when the oscillatory valve is turned from an initial to a pre-determined position, the coin passing from said support and being released from

said valve when the valve has reached said pre-determined position, the valve in passing from the initial to the pre-determined position closing said exit opening, and uncovering said exit opening when retracted to the initial position.

3. In a vending machine, a receptacle for the articles to be vended provided with an exit opening, a rotary delivery member having holes therethrough arranged to consecutively register with said exit opening, a guard covering the hole which is in register with said exit opening, and an oscillatory valve having a slot for receiving a coin and having means, in connection with said receptacle, for supporting the coin in position for engaging and turning said rotary member, when the oscillatory valve is turned from an initial to a pre-determined position, the coin being released from said rotary member when said member has been turned to said pre-determined position and also released from said valve, said valve being arranged to close said exit opening when moved to said pre-determined position and to uncover said exit opening when retracted to the initial position.

4. In a vending machine, a receptacle for the articles to be vended having an exit opening and a coin support, a rotary delivery member having holes therethrough arranged to consecutively register with said exit opening and provided with a plurality of slots corresponding in number to the number of said holes, a guard covering the hole of said delivery member which is in register with said exit opening, and an oscillatory valve having a slot for receiving a coin, and having means in connection with said coin support for supporting said coin when the slot in the valve contains said coin, said slot in said valve registering with one of the slots in the delivery member, when the valve is in the initial position, said rotary member being adapted to be engaged and turned by said coin when the valve is turned from the initial to a pre-determined position, the coin being carried from said support and released by said valve when the valve has been turned to said pre-determined position, the valve being arranged to close the exit opening when the valve is moved to the pre-determined position and to uncover said opening when retracted to the initial position.

5. In a vending machine, a receptacle for the articles to be vended provided in its bottom with an exit opening, a rotary delivery member having a vertical axis and located in the receptacle adjacent to the bottom thereof and provided with a plurality of vertical holes therethrough arranged to consecutively register with said exit opening, and an oscillatory valve disposed in said receptacle intermediate of the bottom

thereof and said rotary member and having the same axis as said rotary member, and having means for supporting, in connection with said receptacle, a coin in position for engagement with and adapted to turn said rotary member when the valve is turned from an initial to a predetermined position, the coin being released from said valve when the valve reaches said predetermined position, the valve being arranged to close said exit opening when moved to the predeter-

mined position and to uncover said opening when the valve is moved to the initial position.

In testimony whereof I have signed this 15 specification in presence of two subscribing witnesses.

OSCAR C. WIESNER.
